UNITED STATES PATENT OFFICE.

JOHAN M. ANDERSEN, OF BOSTON, MASSACHUSETTS.

DESIGN FOR A HANGER.

SPECIFICATION forming part of Design No. 23,244, dated May 1, 1894.

Application filed February 23, 1894. Serial No. 501,309. Term of patent 14 years.

To all whom it may concern:

Be it known that I, JOHAN M. ANDERSEN, residing in Boston, in the county of Suffolk and State of Massachusetts, have invented and produced a new and original Design for a Double Pull-Off, of which the following description, in connection with the accompanying drawings, is a specification, like letters on the drawings representing like parts.

10 The design relates to a double pull off employed to support an insulated hanger for the trolley wire employed in the overhead system of electric railways, and consists in a double pull off distinguished by its peculiar 15 shape, which will be hereinafter set forth and claimed.

Figure 1 shows a front elevation of a double pull off embodying my design, and Fig. 2, a side elevation of the double pull off looking 20 toward the left in Fig. 1.

The leading feature of my design consists in a body portion a made in the shape of a frustum of a cone, and vertically disposed curved arms a' a^2 on substantially diametrically opposite sides of the body portion, which curved arms are integral with the body portion, and at the points of juncture with the body a , extended from near the base to substantially near the top of the said body, so 25 that the arms a' a^2 have a wide appearance at their junction with the body a . The vertically disposed curved arms a' a^2 are each reinforced at its lower curved side with ribs or webs b extended in a downward direction on

opposite sides of the vertically disposed arms 35 from near the base of the frustum shaped body, and the said ribs are curved downward in conformity with the curve of the lower part or edge of the arms a' a^2 and taper toward their outer ends so that they unite with 40 the vertically disposed arms a' a^2 to form at the ends of the said arms, eyes b^2 b^3 of greater thickness than the said arms. The webs or ribs b on opposite sides of the vertically disposed curved arms a' a^2 , are integral with the 45 frustum shaped body a near the base or bottom of the same, and are wider at the point of juncture with the said body and curved downward and outward toward a point or until they merge or unite with the eyes b^2 b^3 . The 50 vertically disposed arms a' a^2 and the strengthening webs or ribs b on opposite sides of each arm a' a^2 , are curved downward a considerable distance below the bottom or base b' of the frustum shaped body a , and the said 55 body at its upper end is covered by a cap c screwed upon the same. The body a is made thicker at its base or lower edge b' .

I claim—

The design for a double pull off herein shown 60 and described.

In testimony whereof I have signed my name to this specification in the presence of two subscribing witnesses.

JOHAN M. ANDERSEN.
